CLAIM

The ornamental design for a fish tape reel, as shown and described.

DESCRIPTION

FIG. 1 is a top, front perspective view of a fish tape reel embodying my new design;

FIG. 2 is a bottom, front perspective view thereof;

FIG. 3 is a top plan view thereof;

FIG. 4 is a right side elevational view thereof;

FIG. 5 is a left side elevational view thereof;

FIG. 6 is a front elevational view thereof;

FIG. 7 is a rear elevational view thereof; and,

FIG. 8 is a bottom plan view thereof.

The broken line representation of holes in FIGS. 2 and 8, as well as the broken line representation of a fish tape, ribs in FIGS. 1-3, and 8, and end piece in FIGS. 1-4, 6, and 8 are for the purpose of illustration only, and form no part of the claimed design.
